UNITED STATES PATENT OFFICE

PAUL PERHATS AND FRANK PERHATS, OF CHICAGO, ILLINOIS

PAPER-TRIMMING MACHINE

Application filed December 10, 1927. Serial No. 239,035.

This invention relates to machines for cutting paper or similar material, and it is especially useful when applied to a machine for trimming paper, cards, booklets, pamphlets, 5 or the like to provide the same with deckle like edges, paneled edges or the like.

The main object of the invention is to provide a paper-cutting or trimming machine which may be operated to trim or cut all of 10 the edges of the paper, or card, in a single operation.

Another object of the invention is to provide a machine of the character described having a plurality of knives arranged to inclose 15 a space and having means for feeding a pile of sheets or cards through the space inclosed by the knives, whereby the edges of said pile of sheets, or cards will be trimmed to a desired size and shape.

20 A further object of the invention is to provide a machine of the character described having means for progressively advancing a pile of sheets or cards with relation to a plurality of knives for trimming or in any other manner operating on all of the edges of said sheets 25 or cards for producing a desired finish on said edges.

A still further object of the invention is to provide a machine of the character described 30 having a plurality of relatively fixed cutting elements each arranged to trim one side of a pile of sheets or cards adapted to be progressively advanced with relation to the cutting elements, and means cooperating with said 35 advancing means for maintaining the pile in a compressed condition during the trimming operations.

A still further object of the invention is to 40 provide a machine of the character described which will have all of the parts thereof mounted on a single casting and which will be capable of operation on sheets or cards of various shapes and sizes and which will be capable of operation on a larger number of 45 sheets or cards at one time for trimming or cutting all of the edges of said sheets or cards.

A still further object of the invention is to 50 provide a machine of the character described having an adjustable table upon which a pile of sheets or cards may be supported, and hav-

ing a cutting element, associated therewith for cooperation with a plurality of other cutting elements which enclose a space through which the pile of sheets or cards is progressively fed for trimming or cutting all of the 55 edges of said pile of sheets or cards.

A still further object of the invention is to provide in a machine of the character described a plurality of cutters adjustable with respect to each other to form an enclosed space of any desired size and means for feeding a pile of sheets or cards with relation to the cutters for trimming all of the edges of said pile, said feeding means having associated with it means for maintaining the said pile of sheets or cards in a compressed condition 60 during the trimming operations.

A still further object is to provide in a machine of the class described a plurality of knives enclosing a space and having a pair of clamps arranged, one on each side of the knives inclosed space, and means associated with said clamps for causing the same to compress a pile of sheets or cards and to feed it 65 while compressed through the space, whereby all of the edges of the pile of sheets or cards will receive a desired operation.

A still further object of the invention is to provide in a machine of the class described a plurality of cutting elements the cutting 70 edges of which are adapted to produce a deckle like edge or the like on a sheet of paper or the like.

A still further object of the invention is to provide in a machine of the class described adjustable supporting means for a pile of sheets or cards to be operated upon, said supporting means having mounted thereon adjustable guides for the sides of said pile, as well as having cooperating therewith engaging means for the top edge of said pile.

A still further object of the invention is to provide a machine of the character described which will be inexpensive and easy to manufacture, simple in operation, durable and compact, and efficient in carrying out the purpose for which it is designed.

With the foregoing and other objects in view, which will appear as the description proceeds, this invention consists in the ar- 100

angement and combination of parts whereby the objects contemplated are attained, and illustrated in the accompanying drawings, which form a part of this application, and in which:

5 Fig. 1, is a longitudinal central section of a paper trimming machine embodying the invention;

10 Fig. 2, is a top plan view of the same, parts of it being broken away;

15 Fig. 3, is a view taken on line 3—3 of Fig. 1 looking in the direction of the arrows;

20 Fig. 4, is a cross sectional view of one of the knife elements;

25 Fig. 5, is a top plan view of the element shown in Fig. 4; and

30 Fig. 6, is a side elevation of the same.

Referring to the specific embodiment of the invention illustrated by way of example in the drawings, the operative parts of the machine are mounted upon a box-like casting 1 comprising the bottom 2, having suitable feet for support on a floor or the like, side portions 3, and end portions 4 and 5, the end portion 4 being considerably higher than the side portions 3 and is provided with a substantially rectangular opening 6 therein, for a purpose to be hereinafter described. The end portion 5 extends a sufficient distance above the side portions to provide therein a thrust bearing 7, for a purpose to be hereinafter described. The casting 1 is of such size and proportions as to provide a rigid foundation for the operating mechanism of the machine, and will be capable of permitting an efficient operation of the machine for the purpose for which it is designed, namely, that of trimming the edges of a pile of sheets or cards in a single operation.

35 40 The top of said box-like casting 1 is open and is adapted to receive therein a supporting table 10, said table being adapted for vertical adjustment relative to said casting. The adjustable means for said table comprise a screw 11, having its upper end fixed to a table, as by the pin 12, or in any other suitable manner, and having its lower end received in a bearing 13 provided therefor in the base 2 of the casting 1. Mounted on said screw intermediate the ends thereof is a hand wheel 14, which is threaded thereon. Because of the weight of the table, the hand wheel 14 will obviously rest on the bearing 13 at all times, thus by rotating the hand wheel the table may 45 be raised or lowered to any desired position.

50 55 In order to guide the table 10 in its up and down movement the said table is provided with a plurality of grooves or notches 15, one near each corner thereof, said grooves being adapted to receive the tracks of projection 16, formed on said side portions 3, and upon which the said table is adapted to ride or slide as it is moved in either direction. It will thus be noted that the table 10 is of a size to substantially close the opening in the top of the

casting and that it is securely held in any desired adjusted position on said casting, said table being normally held in position above the level of the bottom of the opening 6 in the end member 4.

55 60 Means are provided for advancing the pile of sheets or cards to be trimmed, which pile is supported on the table 10. These means may be widely varied in construction and arrangement but in the construction shown there is provided means for advancing the pile along the supporting table 10 to be acted upon by the cutting mechanism to be hereinafter described. In the machine shown the feeding mechanism acts to advance the pile with a progressive movement such as is associated

65 70 with the insertion of the untrimmed sheets or cards at one point and the removal of the trimmed product at another point. In the specific construction shown the mechanism operates to advance the pile with relation to the trimming mechanism and to feed the said pile past the said mechanism. As shown, this advancing or feeding mechanism comprises

75 80 a head or member 20 adapted to engage the forward end of the pile and a head or member 21 adapted to engage the rearward end of the pile, said heads being respectively mounted upon crossheads 22 and 23 arranged to slide on the horizontal guide bars 24 and 25 rigidly

85 90 fixed at the opposite sides of the casting 1, in bearings provided therefor in said casting. Preferably the advancing mechanism is constructed to compress or clamp the pile during

95 100 the trimming operation. This may be accomplished by mechanism which varies widely as to form and arrangement.

105 110 In the particular construction shown the crosshead 23, has extending therethrough a screw 26, to the forward end of which is rigidly secured the head 21 by means of a screw 27, or in any other suitable manner. The following means are provided for rotating to said screw 26 in order to move the head 21 towards or away from the head 20. Threaded on the

115 120 screw 26 is a toothed wheel 28, the hub of which wheel 28 has a frictionless bearing in the crosshead 23, said wheel is adapted to mesh a worm 29, provided on one end of a shaft 30, the other end of which is received in a horizontally disposed bearing 31, provided therefor and formed integral with the crosshead 23. The said shaft 30 extends just

125 130 a small distance beyond the said bearing and has secured on the free extended end thereof a hand wheel 32, provided with a handle 33 for rotating the same. The hand wheel 32 is arranged to extend just beyond the side of the machine. It will be noted that upon manipulation of the hand wheel 32, the worm 29 will

135 140 be rotated to cause a rotation of the toothed wheel 28, which will in turn cause a rotation of the screw 26, moving the head 21 towards or away from the head 20.

145 150 As shown, the cross-heads 22 and 23 are

adapted to be moved in unison, by means of the screw 34, which is mounted for rotation in the frictionless bearing 7, provided therefor in the end member 5 of the casting 1, the said 5 crossheads 22 and 23 being rigidly connected with each other by means of the side rods 35 and 36, one end of which rods is rigidly secured to the crosshead 22. The crosshead 23 is adapted for sliding movement to along the 10 length of said rods and means are provided for holding the said crosshead 23 in fixed relation on said rods at certain predetermined points on said rods. This means comprises openings 37 provided in said rods at certain 15 spaced intervals along its length, which openings are adapted to receive a pin 38, or the like, extending through the crosshead 23 for securely locking the said cross-head to the rods 35 and 36 and thereby securely connecting the crosshead 22 with the crosshead 23, whereby the two may move in unison.

Any suitable means may be employed for moving the crosshead 22 along the top of the casting and with respect to the supporting 25 table 10. As shown, the screw 34, is provided for this purpose, one end of which is rigidly secured in the cross-head 22, and the other end of which extends through a sleeve 35' provided in the frictionless bearing 7, and beyond 30 the end member 5. The sleeve 35' extends a small distance beyond the bearing 7 and has mounted thereon a toothed wheel 36', or the like, which is adapted to mesh with a worm, or the like, provided on the shaft of a motor 35 (not shown). Rotation of the wheel 36' in the proper direction will cause a movement of the cross-head 22 in the desired direction.

Any suitable trimming mechanism may be employed and the same may be arranged to 40 trim one or all sides of the pile of sheets or cards as desired. In the construction shown in the drawings the trimming mechanism consists of a plurality of knives, preferably four in number, each arranged along one side of 45 the opening 6, provided in the end portion 4, of the casting, to form an inclosed space, the space shown in the drawings being of substantial rectangular cross section. As shown, a knife 40 is provided to trim the upper edge 50 of the pile, a knife 41 is provided to trim the lower edge of the pile, and the vertical knives 42 and 43 are provided to trim the two side edges of the pile. The knife 40 is mounted in a knife block 44, in any suitable manner, 55 the said knife block 44 being arranged for vertical adjustment in the opening 6. The adjusting means may comprise a pair of vertically positioned screws 45, extending through the top side of the opening 6, and each threaded through the knife block near the ends thereof, each of said screws having a hand wheel 46 at one end thereof for rotating the said screws. Collars 47 are provided 60 on each of said screw members for preventing any vertical movement of said screws. It

will be obvious that upon operation of the hand wheels 46 the screws will be rotated to move the knife block 44 with its knife 40 in the desired direction and to any desired adjusted position.

The knives 42 and 43 are mounted in knife blocks 48 and 49 respectively, said blocks being adapted for movement towards and away from the center of the opening 6. The means for causing the adjustment of each of said knife blocks will now be explained. Since the means employed for each knife block is exactly similar, only one will be described in detail. As shown, the knife block 48 is provided near each end with a projection or ridge 50, adapted to be received and ride in a groove or runway 51, provided therefor in the upper and lower sides bordering the opening 6, in the end portion 4, of the casting, the said blocks being held in the grooves or runways 51 by the plates 52 which are secured in any suitable manner, as by screws 53, or the like, to the end member 4, as shown in Fig. 3, of the drawings. It will thus be noted that the knife blocks 48 and 49 are adapted to slide in the runways 51 towards and away from the center of the opening 6. Any suitable means may be employed for adjusting the knife blocks, however, we have found the following to be most satisfactory. A pair of screws 54 are adapted to be threaded through the knife block 48, one near each end thereof, the said screws having bearings provided for them in the end member 4, as shown in the drawings. Means are provided on each screw for preventing sliding movement thereof in its bearing. The upper screw 54 is provided at the outer end thereof with a hand wheel 55, or the like for rotating the same. In order that the upper and lower screws may be operated in unison, a chain and sprocket 56, is rigidly mounted on each screw, and an endless chain 57 is passed over these sprockets, whereby rotation of the upper screw will be transmitted to the lower screw. It will thus be noted that in order to adjust the position of the knife block 48, the hand wheel 55 need only be rotated in proper direction. In a similar manner the knife block 49 may be moved to any desired adjusted position.

The lower knife 41 is carried on the knife block 58, which block is rigidly secured to the supporting table 10, by means of the screws 59, or in any other suitable manner, so as to move with said table, as the lower knife should be at all times on a level with the top of the table 10. The table 10 is also provided with a projection 60, adapted to bridge the space between the end of the table and the knife 41, which is spaced from the table as the vertical knives 42 and 43 are in front of the knife 41.

A supporting table 61, having a depending supporting rod 62 adapted to be received in a bearing 63 provided therefor on the casting

1, is provided in rear of the knives. The said table being held in any desired adjusted position by means of the set screw 64. In operation the table 61 is adjusted to the same level as the supporting table 10.

5 As shown, the supporting table 10 is provided on its upper surface with a pair of laterally adjustable side guides 65 and 66, the guides being adjustable inward or outward by means of the screws 67, threaded in the top of the table 10, and received in the slots 68. By loosening the screws 67 in the slots 68, the guides may be moved to any desired position, and can be secured in this 10 position by tightening the screws 67.

15 As shown, means are also provided for engaging the top edge of the pile of sheets or cards. This means may comprise the arm 70, which may be hingedly mounted on a bracket 20 71, which bracket may be adjustably mounted on a rod 72, the lower portion of which rod is rigidly held in a portion of the end member 5 of the casting 1. A set screw 73, or the like, may be provided on the bracket 71 25 for holding the same in any desired adjusted position on the rod 72. The forward end of the arm 70 is adapted to engage a bracket 74, secured to the knife block 44, the said forward end of the arm being detachably secured to 30 said bracket 44, by means of a wing nut 75, and a screw 76, secured to the bracket. It will thus be noted that the pile of sheets or cards is guided on all four edges thereof.

35 It is to be understood that any suitable knife or cutting element may be employed, the shape of the knife, depending upon the nature of the edge desired. The knife element shown in the drawings may comprise the cutting edge 80, the beveled surface 81 40 and the base or body of the knife 82. The inner face 83 of the knife, shown in the drawings, is provided with grooves or corrugations 84, for the purpose of producing deckle like edges on the sheets or cards being 45 operated upon. If any other type of edge is desired a trimming element suitable for producing the desired edge may be substituted for the cutting element shown in the drawings.

50 The operation of the machine will be readily understood from the description of the construction thereof. The pile of sheets or cards to be operated upon is placed upon the table 10, between the side guides 65 and 66, the said guides being then adjusted to their proper position on the table whereby they will engage the side edges of the pile. The arm 70 is then swung down in position to engage the top edge of the pile. Of course, it is to be understood that the knives have already been 55 adjusted to their proper positions for receiving the size of cards to be acted upon and also the cross-head 23 has been positioned at the proper point along the rods 35 and 36, depending upon the number of cards to be 60

trimmed, that is, the thickness of the pile, and the head 21 has been moved to approximately the point where it is to engage the rearward end of the pile. The cards are placed between blocks of wood or the like which blocks of 70 wood are adapted to be supported on the screws 85 provided therefor on the heads 20 and 21. After the cards have been placed on the table 10, with one edge of the pile engaging the head 20, the hand wheel 32 is 75 rotated to bring the head 21 into engagement with the rear end of the pile, and this head 21 is moved until the pile is securely clamped between the two heads 20 and 21.

80 After the pile has been properly positioned and clasped, the motor is started, causing a rotation of the wheel 36', which will cause a progressive advancement of the crossheads 22 and 23, which will carry the pile past the cutting knives, which knives will trim the 85 edges thereof. When the whole pile has passed through the opening inclosed by the knives, the motor may be stopped, and the hand wheel 32 operated to release the cards from between the heads 20 and 21, and the 90 cards removed.

95 It will be seen that the machine is simple and compact in construction, that it may be operated without the exercise of great care or skill, and that all of the edges of a pile of cards or sheets may be trimmed or cut in one operation, and that a great number of sheets or cards may be acted upon at one time, at a fair rate of speed.

100 While we have particularly described our invention as embodied in a deckling machine, it is to be understood that the invention in its broader aspects is not limited to a machine designed for this particular purpose nor to the particular construction shown or described, as 105 many changes may be made in the mechanism by which the invention is carried into effect, depending upon the particular work to be performed and upon the judgement and skill of the designer; without departing from the 110 main principles of the invention, as defined in the appended claims, and without sacrificing its chief advantages.

115 Having thus described our invention, what we claim and desire to secure by Letters Patent is:

1. In a paper trimming machine, the combination with a plurality of relatively adjustable knives arranged to inclose a space, of means for feeding a pile of sheets or cards through the space inclosed by the knives, whereby all of the edges of said pile may be 120 trimmed at one time, and an adjustable support on each side of said space for holding and receiving said pile of sheets or cards.

125 2. In a machine of the character described, the combination of trimming mechanism, and means for progressively advancing a pile of sheets with relation to the trimming mechanism in a direction transverse to the plane 130

- of the sheets, said means comprising a pair of crossheads adapted to move in unison, means carried by said crossheads for clamping the said pile therebetween and holding the said pile in clamped condition during the trimming operations, and an adjustable support for receiving said cards after they have been trimmed.
3. In a paper trimming machine, the combination with an adjustable support for a pile of sheets or cards, guides for said pile, of a plurality of knives, a second adjustable support at the other side of said knives for receiving said cards after they have been trimmed, a pair of cooperating jaws one on each side of the knives, and means for causing the jaws to compress the pile and to feed it while compressed past the knives for trimming the edges of said pile.
4. In a paper trimming machine, the combination with an adjustable table arranged to support a pile of sheets or cards, guides carried by said table and adapted to guide said pile on two sides, of a plurality of knives arranged to trim all of the sides of said pile, a pair of cooperating jaws arranged one on each side of the knives, means cooperating with one of said jaws for causing said jaws to compress said pile, and means for feeding said pile past the knives while in compressed condition.
5. In a paper trimming machine, the combination with a plurality of knives arranged to inclose a space, of means for adjustably supporting a pile of sheets or cards in operative relation to said knives, a pair of cooperating jaws operating on opposite ends of the pile, means connected with one of said jaws for operating the same to compress the pile, means for producing movement of the pile relative to the knives, whereby the knives are caused to trim the sides of the pile, and means associated with said knives for varying the space inclosed thereby.
6. In a trimming machine for sheets or cards, the combination with a trimming machine for sheets or cards, the combination with a trimming mechanism, of means for supporting the sheets or cards, means for producing a relative movement between said sheets or cards and said trimming mechanism, by which the trimming is effected, said movement causing the sheets or cards to pass during the trimming operation from one side of the trimming mechanism to the other, an adjustable support for receiving said cards after they have passed the said trimming mechanism, a clamping mechanism comprising a pair of cooperating jaws arranged one on each side of said trimming mechanism, means for operating said clamping mechanism on one of said jaws, and means for progressively feeding said pile past said trimming mechanism while the pile is in compressed condition.
7. In a machine for trimming a pile of sheets or cards, the combination of relatively fixed cutters, a device for clamping the opposite ends of said pile, means for advancing the pile with relation to the cutters in a direction transverse to the plane of the sheets while the pile is being held in compressed condition, and means for guiding the said pile on all sides thereof during its advancing movement.
8. In a machine of the character described, the combination with a box-like casting having one end portion thereof extending above the adjacent sides thereof, and provided with an opening therein, of a plurality of cutters bordering said opening, an adjustable support on one side of said cutters arranged to support a pile of sheets or cards, means for advancing said pile relative to said cutters in a direction transverse to the planes of the sheets and means for clamping the pile during the advancing movement.
9. In a machine of the class described, the combination with a casting having a trimming mechanism at one end thereof, an adjustable support carried by said casting for supporting a pile of sheets or cards, means for causing the said pile to be fed past said trimming mechanism, and means for clamping the said pile during its advancing movement, said means comprising a pair of jaws arranged one on each side of said trimming mechanism.
10. In a device of the character described, the combination with a casting having an adjustable bed thereon arranged to support a pile of sheets or cards, a plurality of cutters carried by said casting at one end of said bed, means for clamping said pile on said bed, means for feeding said pile past said cutters, and a table carried by said casting on the side of said cutters, opposite that of the bed for receiving the cards as they pass the cutters.
11. In a device of the character described, the combination with a casting having an upstanding end portion provided with an opening therein, of cutters bordering said opening, an adjustable bed arranged to support a pile of sheets or cards on one side of said cutters, means for clamping the pile while in position on said bed, said clamping means comprising a relatively fixed jaw on one side of said cutters and a movable jaw on the other side of said cutters for trimming the sides thereof, said means comprising a pair of crossheads arranged one on each side of said cutters and adapted to be moved in unison and one of said crossheads being operatively connected with a screw for advancing the same relative to the bed.
12. In a machine of the character described, the combination with a casting having a trimming mechanism at one end thereof, a bed on one side of said trimming mech-

anism, arranged to support a pile of sheets or cards, means for feeding said pile past said trimming mechanism, said means comprising a pair of crossheads, one on each side of said trimming mechanism, said crossheads being releasably connected with each other for movement in unison, clamping means carried by said crossheads for compressing the said pile during its advancing movement, and means operatively connected with one of said crossheads for causing the same to advance past the said trimming mechanism.

13. In a machine of the character described, the combination with a casting having a trimming mechanism at one end thereof, of a table arranged to support a pile of sheets or cards on one side of said trimming mechanism, guides carried by said table for guiding the said pile, means for advancing the said pile with relation to the trimming mechanism, said means comprising a pair of releasably connected crossheads arranged one on each side of said trimming mechanism and a screw operatively connected with one of said crossheads, and means carried by said crossheads for clamping the said pile and holding the same in compressed condition during its advancing movement.

14. In a paper trimming machine, means for clamping together a plurality of sheets or cards, a plurality of spaced cutting elements inclosing a space, means for moving the said sheets or cards to be trimmed into engagement with the cutting elements, and means for guiding the said sheets or cards on all sides thereof during their advancing movement.

15. In a paper trimming machine, means for clamping together a plurality of sheets or cards, a plurality of cutters arranged to inclose a space, each of said cutters having a cutting edge and a corrugated face adjacent thereto for producing a deckle like edge on said sheet or card, and means for moving the said sheets or cards into engagement with the cutters whereby the same may be trimmed thereby.

In testimony whereof we affix our signatures.

PAUL PERHATS.
FRANK PERHATS.
